UNITED STATES PATENT OFFICE.

FRIDOLF OLSON, OF BROOKLYN, NEW YORK.

COLUMN MOLD.

1,405,934.

Specification of Letters Patent. Patented Feb. 7, 1922.

Application filed September 5, 1919. Serial No. 321,785.

To all whom it may concern:

Be it known that I, FRIDOLF OLSON, a citizen of the United States, and a resident of Brooklyn, county of Kings, and State of New York, have invented certain new and useful Improvements in Column Molds, of which the following, together with the accompanying drawings, is a specification.

This invention relates to apparatus for the casting of columns and structures of like character.

The objects of the invention are to provide a mold for this purpose which will be adjustable for columns of different height, which will be simple and substantial in construction and which will be capable of being quickly assembled and disassembled.

These objects I have accomplished in part by constructing the mold with longitudinally extensible telescopic sections and by the provision of simple means by which said telescopic sections may be readily adjusted with respect to each other. Other features relate to the manner in which the separable parts of the mold sections are held in assembled relation and certain details of construction.

In the accompanying drawings, I have illustrated but one embodiment of the invention, but would have it understood that structural features may be modified to suit the various requirements without departure from the true spirit and scope of the invention as defined in the appended claims.

Figure 1 of these drawings is a partly sectional view illustrating the mold adjusted to a short column.

Figure 2 is a similar view showing the mold adjusted for a longer column.

Figure 3 is a plan view of the mold on an enlarged scale.

Figures 4, 5 and 6 are cross sectional views taken substantially on the planes of the lines 4-4, 5-5, 6-6 of Figure 2.

Figure 7 is an enlarged detail view of the adjustable support for the head portion of the mold.

Figure 8 is an enlarged detail view of the connection between the upper column section and the head section of the mold.

Figures 9 and 10 are detail sectional views of the relatively staggered securing means for the separable parts of the mold sections.

Figure 11 is a detail view of the upright or column portion of the

mold comprises in the present disclosure an intermediate tubular mold section 12, and upper and lower mold sections 13 and 14, telescopically engaged in the opposite ends of the same. These mold sections are adjustably secured together by connections consisting in the illustration of the bolt rods 15 engaged at one end with annular outstanding flanges or abutments 16 on the end sections (13, 14) and having angularly bent hooked portions 17 at their opposite ends adapted to be hooked into longitudinally spaced openings 18 on the outstanding ribs or flanges 19 of the intermediate mold section. The bolts are adjusted according to this present disclosure by wing nuts 20 engaged with the ends of the bolts and having a bearing against the outstanding flanges 16.

In practice, when the sections are set up, a rough adjustment is secured by engaging the hooked ends of the stay bolts 15 into the nearest openings in the outstanding ribs on the intermediate section and then the wing nuts are turned to effect the final adjustment of the telescopically engaged mold sections. By providing wing nuts at both sides of the flanges or abutments 16, it will be evident that the bolts may be adjusted in both directions either to contract or expand the mold longitudinally.

To facilitate the quick engagement of the connecting means, I have shown the flanges 16 as provided with bayonet slots 21^a cut inward from the edges thereof to receive the bolts 15. With this arrangement when the nuts are loosened or removed the bolts may be quickly set in the bayonet slots and engaged with the proper holes in the anchorage ribs 19.

The cap or head portion of the mold is designated 21 and the same is shown secured to the upper column section by means of abutting flanges 22, 23 on such adjoining sections which are connected by the bolts 24 which are shown as releasably engaged in the bayonet slots 25 formed in the edges of the abutting flanges.

Similarly the top 26 of the mold is shown secured to the cap portion of the mold by the bolts 27 engaged in the bayonet slots 28 provided in the abutting flanges 29.

The several mold sections are separable to permit the mold being removed from the

complete column. The column sections are shown formed each in two parts having the edges thereof abutting, as indicated at 30. These edges are secured in this relation by 5 the angle irons 31, 32 fastened along the edge portions of the two parts and arranged as indicated in Figure 9, so that the angle iron 31 on one part projects beyond the edge of the mold part to which it is secured and provides a seat at 33 for the edge of the other mold part which as indicated, projects beyond the base part of the angle iron which is secured to such other part. In assembling 10 the sections, these joints are offset or staggered as indicated in Figures 1 and 2, and as shown in Figures 9 and 10.

Suitable means are provided for clamping the flanges together, said means consisting in the present disclosure, of relatively short 20 bolts 34 provided with readily adjustable wing nuts 35.

In Figure 7, I have shown how the head of the mold may be adjusted and secured to the adjacent framing which is indicated at 25 36. This adjustment is secured by means of a wedge 37 inserted between the framing and an angle brace 38 at the edge of the top portion of the mold. When the proper adjustment of these parts is secured they may 30 be fastened in such relation as by means of nails 39 or other suitable fastenings.

What I claim is:

1. A longitudinally extensible column mold comprising an intermediate tubular mold section and tubular sections telescopically engaged with the opposite end portions of the same, an outstanding longitudinally extending rib on the intermediate section provided with a series of spaced shoulders, 40 abutments on the end sections, and links adjustably connected between said abutments and selected shoulders on the rib for adjusting the relation between the intermediate mold section and the sections at the opposite 45 ends of the same.

2. A longitudinally extensible column mold comprising telescopically engaged tubular mold sections, an external longitudinal flange on one of said sections provided with a series of spaced shoulders, an abutment on the other section, and a link adjustably connected with said abutment at one end and having a hooked portion at its opposite end for engagement with different shoulders on the 55 outstanding flange.

3. A longitudinally extensible column mold comprising an intermediate tubular mold section, mold sections telescopically engaged in opposite ends of said intermediate section, external longitudinally extending ribs on the intermediate section provided each with a series of openings, external flanges on the end mold sections, and bolts adjustably engaged with said flanges and provided with

angular end portions for hooked engagement 65 in the openings in the ribs.

4. A longitudinally extensible column mold comprising telescopically engaged tubular end and intermediate mold sections, each of said mold sections being separable longitudinally into separate parts, means for securing the separable parts of the mold sections in assembled relation, external longitudinally extending ribs on one of the sections provided each with a series of openings, an 70 external flange on the adjacent section and bolts adjustably engaged with said flange and provided with angular end portions for hooked engagement in the openings in the 75 ribs.

5. A column mold comprising a tubular intermediate mold section, mold sections telescopically engaged in the opposite ends of the same, all of said sections being separable longitudinally to open the mold and said 80 end mold sections having means for securing the separable parts of the same in assembled relation, said means terminating a distance short of the ends of such mold sections to enable the end mold sections to telescope 85 within the intermediate mold section, and connecting means between the end and intermediate mold sections adjustable to enable telescopic adjustment of said sections.

6. A column mold comprising telescopically engaged mold sections, flanges on the relatively adjustable sections and bolts engaged between said flanges for securing the sections together, said flanges having bayonet slots formed in the edges thereof to enable the ready engagement of the securing bolts therewith.

7. In a mold of the character described, mold sections having abutting annular flanges provided with bayonet slots in the 105 edges thereof and securing bolts engaged in said bayonet slots.

8. In a column mold, telescopically engaged mold sections, adjustable connections between said telescopically engaged sections for shifting the sections telescopically with respect to each other, a mold section for casting the cap of the column detachably engaged with the uppermost column section, means for adjusting said cap mold section 110 with respect to a stationary framing and securing means for said cap mold section engaging said adjusting means.

9. In a column mold, telescopically engaged tubular mold sections and consisting 115 each of longitudinal separable parts, and flanges for securing the parts in assembled relation disposed in alternating relation in the length of the mold at opposite sides of the meeting edges of the mold parts.

In witness whereof, I hereunto set my hand, this 26 day of August, 1919.

FRIDOLF OLSON.
